UNITED STATES PATENT OFFICE.

FRANK KUSTEELE, OF KENOSHA, WISCONSIN, ASSIGNOR TO SIMMONS COMPANY, OF NEW YORK, N. Y., A CORPORATION OF DELAWARE.

MATTRESS VENTILATOR.

Application filed May 10, 1926 Serial No. 107,891.

This invention relates to mattress ventilators, and more particular to ventilators for mattresses, cushions and the like, the covers or ticks of which are provided with a number of openings therein, through which air may circulate to the interior of the mattress or cushion.

The objects of the invention are to provide means for preventing the mattress filling from coming out through the holes in the tick which means will permit free circulation of air therethrough and which will be simple and economic to make, of rigid construction, and which will be provided with means for attachment to the mattress tick whereby it will not readily or accidentally be pulled therefrom.

Other objects and advantages of the invention will become apparent when the following specification is considered in connection with the accompanying drawing wherein I have illustrated a selected embodiment of the invention, and in which:

Fig. 1 is a plan showing a ventilator according to the present invention, in place on a mattress tick.

Figs. 2 and 3 are sections which illustrate successive steps in the construction of the ventilator, and

Fig. 4 is a section on the line 4—4 of Fig. 1, and illustrates the method of fastening the ventilator to the tick.

Referring now to the drawings, and more particularly to Figs. 1 and 4, a ventilator according to the present invention is indicated at 5, secured to a mattress tick or cushion covering 6. The ventilator 5 comprises a metal tube T having a reticulated closure portion 6 extending thereacross, and provided with an outwardly extending flange 7 against which the edges of the mattress tick, around an aperture therein through which the ventilator passes, is adapted to be clamped or pinched by means of another flange 8.

The construction and application of the ventilator is as follows: The first operation is to form a cup such as shown in Fig. 2. This cup is provided with a tubular portion 9 and an end closure 10 which is preferably recessed as shown. The second operation is to punch suitable holes 11 in the recessed end closure 10 as indicated in Fig. 3. The next operation is to swage the tubular portion 9 inwardly into the form shown in

Fig. 3 to provide a shoulder 12, and an upwardly extending tubular portion 13. The mattress tick 6, to which the ventilator is to be applied is provided with an aperture 14, which is preferably of smaller diameter than the outside diameter of the tubular portion 13. The tubular portion 13 of the ventilator is then projected through the said aperture 14 until the mattress tick rests on the shoulder 12 as shown in dotted lines in Fig. 3. It will be observed that a portion of the tick 15 immediately adjacent the aperture will be forced to turn upwardly or outwardly with the projecting tubular portion 13 and will be caused to lie thereagainst and this by reason of the greater diameter of the tubular portion 13, as compared with the diameter of the aperture 14.

The ventilator is secured in position on the mattress tick by turning the projecting tubular portion 13 outwardly over the shoulder 12 whereby the portion 15 of the tick will be folded upon the adjoining portion of the tick so as to provide a double edge around the aperture. The tubular portion 13 is turned outwardly and sufficient pressure applied downwardly so as to tightly clamp the tick between the said shoulder 12 and overturned tubular member 13, which becomes a flange as indicated at 8 in Fig. 4. It will be observed from an inspection of Fig. 4 that the shoulder 12 is preferably pressed down against the marginal portion of the closure member 6 so as to form the flange 7 of double thickness without any intervening space whereby the finished flange 7 is of double thickness but is nevertheless comparatively thin, and therefore will not project beyond the tick to an objectionable degree.

By causing the edge of the tick adjacent the aperture to be folded upon itself, so as to provide a double thickness edge around the aperture, the ventilator is afforded a reinforced edge on which it may be clamped. By this means the possibility of accidental or easy pulling out of the ventilator is largely eliminated as it will be obvious that the said double edge will not readily tear or pull out from between the flanges 8 and 12. I have thus provided a ventilator constructed of one piece which may be easily and economically manufactured and secured in place on a mattress tick, and through which air may freely circulate.

I am aware that various changes in form,

construction and proportion or parts may be made without departing from the essence of the invention, and I therefore reserve the right to make such changes as fall within the scope of the following claim.

I claim as my invention:

In a ventilated mattress, the combination of a tick portion having an aperture therein, a tubular member having a reticulated clo-
10 sure member extending thereacross, said tubular member being of greater outside size than the size of said aperture and being adapted to be inserted into said aperture so as to project therethrough, whereby a portion of
15 said tick adjacent said aperture will be caused

to lie along said tubular member, a shoulder at one end of said tubular member for positioning the latter with respect to said tick, said projecting portion of said tubular member being adapted to be swaged outwardly 20 and towards said shoulder so as to effectively clamp the tick surrounding said aperture between said shoulder and the swaged portion of the tubular member, said tick portion being folded over on the surrounding tick by 25 reason of said swaging operation so as to form a double edge of ticking around said aperture and between said shoulder and swaged portion.

FRANK KUSTERLE.
